UNITED STATES PATENT OFFICE.

CHARLES E. WILLIAMS, OF WESTFIELD, MASSACHUSETTS..

MACHINE FOR TWISTING SNAPS FOR WHIPS.

SPECIFICATION forming part of Letters Patent No. 277,967, dated May 22, 1883.

Application filed April 22, 1882. (No model.)

To all whom it may concern:

Be it known that I, CHARLES E. WILLIAMS, of Westfield, in the county of Hampden and State of Massachusetts, have invented a new and useful Improvement in Machines for Twisting Snaps for Whips, of which the following is a specification and description.

The object of my invention is to provide a machine to twist snaps of any desired length, and from a series of continuous threads or strands, and by which snaps may be uniformly twisted, each composed of threads or strands made of different material, and by which snaps of different lengths may be twisted and finished without stopping the machine; and I accomplish this by the mechanism substantially as hereinafter described, and illustrated in the accompanying drawings, in which—

Figure I is a perspective view of my invention, showing both the upper and lower portions of the machine, and the arrangement of geared wheels for rotating the racers, one of the legs of the table being broken away to show the parts of the machine beyond. Fig. II is a perspective view, showing the upper part of the machine; and Fig. III is a reverse plan view of the machine.

In the drawings, 1 represents a table or bench properly supported, and in which is a suitable thimble or sleeve, 52, preferably of metal, and placed in a vertical position, through which extends a tube, 2, and in which said tube has its bearing, so as to revolve freely. This tube is secured fast to a large toothed wheel, 18, with a plate or disk, 4, above said wheel, and a similar plate, 5, below it, resting upon the sleeve 52 in the table, and I secure these two plates together by bolts or rivets, with the tube extending through said plates, so that the latter may revolve independently of the tubes. The plates 4 and 5 are fitted to the tube 2 sufficiently loose to permit the latter to revolve on its axis independently of said plates, or while they remain stationary. To prevent the plates from tilting into an inclined position while resting on the top of the sleeve 52, I secure a collar, 50, to the tube just above the upper plate, 4, which operates to keep the plates in a horizontal position, even when the friction-roll 50 is forced down thereon, as hereinafter described.

A series of toothed wheels, 17, are arranged to revolve between the plates 4 and 5, each said wheel fixed to a shaft or spindle having its bearing at its lower end in the lower plate, 5, and which shaft extends up through the upper plate, 4, with a hub, 53, secured to its upper end, said wheels being so disposed that their teeth may engage with the teeth of the large toothed wheel 18. A disk secured to each hub has an upright post, 7, secured thereto, upon which, as a spindle, is to be placed a tubular spool, upon which the material to be twisted is wound, and whose upper end is provided with ratchet-teeth 8. A post, 10, is also secured to said disk and extends up to a point somewhat above the spool, with a piece at its upper end, which projects toward and partially over the spool and is provided with an eye, 55. As this piece is permanently fixed to the post, I propose in practice to make it and the post all in one piece, to obviate any liability of its getting loose. Two projections or buttons, 11, are made on said post, one near its upper end and the other at some distance below and upon opposite sides of the post. A spring, 12, is attached to the disk connected with the hub 53, with a hook at the upper end of said spring; and a rod or wire, 9, is inserted in the upper end of each spool, the upper part of which rod extends outward, nearly at a right angle to its lower part, directly over the upper end of the spool, and engages with the ratchet-teeth 8 thereon. The extreme end of the horizontal part of said rod bears against the post 10.

A shaft, 19, is supported in suitable bearings beneath the table, upon which I place two pulleys, 56 and 57, side by side, one loose, and the other fast to the shaft. A bevel-gear wheel is fixed to the end of said shaft, and a corresponding bevel-gear wheel is fixed to the lower end of the tube 2, which extends down through its bearing in the table, both bevel-gear wheels being shown engaged together at 20. A rod, 3, located within the tube 2, is provided at its upper end with a head, 15, fitted so as to revolve freely thereon, and this head is provided with a series of thread-grooves, 16, each adapted to receive a thread or strand extending up from one of the spools. This rod 3 extends down through the tube 2 to a point

below the bevel-gear wheel on the lower end of the tube, with a projection, 21, on the lower end of the rod.

- 5 A vertical box, 22, is secured fast beneath the table, with a vertical slot or opening, 23, through one side, and the projection 21 extends through this slot or opening into the box, so that as the rod 3 moves either up or down the projection will have a corresponding movement within the box. A small pulley, 26, is secured in the upper part of the box, with a band or chain, 27, extending over it, one end of which is secured to the projection 21 within the vertical box, and the other end is secured to a weight, 30, outside the box, so that when there is no thread or material to be twisted in place in the machine the said weight will cause the rod 3 to rise to its highest position within the tube 2.
- 20 A rod, 24, is supported by a ledge or projection on the box 22, and is held in a vertical position by the side of the box 22 by means of suitable bearings or guides, so that said rod may move freely either up or down. An adjustable dog, 25, is adapted to be secured by a set-screw at any desired point on the rod, and a vertical hole is made in the dog, through which the band or chain 27 may pass freely while the dog remains stationary.

- 30 A lever, 36, is pivoted to the lower side of the table, one arm of which extends out directly above the upper end of the rod 24, and whose other arm is adapted to engage with and hold back one arm of another lever, 28, pivoted to the lower side of the table.

- 40 A belt-shifter, 29, is secured and slides in bearings beneath the table, the same being pivoted to the lever 28, as shown in Fig. 3. This belt-shifter is operated in one direction to stop the machine by spring 37 when the lever 36 is tripped by the rod 24. To set the machine in motion, the operator moves lever 32, which extends up in front of the machine, and therethrough moves lever 28, so that it engages with lever 36. In this position the machine continues in operation until lever 36 is again tripped by rod 24.

- 50 An arm, 13, is pivoted to the table and extends through or beneath a fixed piece, 39, through which is turned a thumb-screw, 38, whose lower end bears upon said arm and operates to press a friction-roll, 14, pivoted in the free end of said arm upon the plate 5 with more or less force, according as the thumb-screw is turned in or out of the piece 39 more or less. There is of course considerable friction in the working of the toothed wheels 17 with the toothed wheel 18, and if the friction-roll 14 is not pressed down on the plate 5, upon turning the shaft 19 the plates 4 and 5 will be caused by this friction to revolve with the tube, and the toothed wheels 17 and hubs 53 will not revolve upon their own axes; but if the friction-roll be pressed down with sufficient force to check the speed of the plates somewhat, the wheels 17 and hubs 53 will be made

to revolve on their axes at the same time the plates are revolved around the axis of the tube. By this construction the relative speed of revolution of the hubs 53 around their axes and of the plates 4 and 5 around the axis of the tube 2 may be varied by forcing the friction-wheel 14 down upon the plate 5 more or less, until, if forced down with sufficient pressure, the said plates will be prevented from revolving around with the tube, while the toothed wheels 17 and the hubs connected therewith will continue to revolve.

The spools containing the material to be twisted are placed each upon a spindle, 7, and the thread is passed around the lower projection 11 from its lower side, thence upward to the opposite side of the post 10, and over the upper projection 11, thence down over against the horizontal part of the wire 9 on the side 85 opposite said post into the hook in the upper end of the spring 12, thence upward on the other side of the wire 9 through the eye 55 in the projecting top of the post 10. Each thread, being disposed in the same manner, is extended upward and inserted in a groove, 16, in the head 15, and they are all secured together above the latter, and may be fastened to a hook or suitable fastening to draw them away from the twisting mechanism. The dog 25 is 95 then adjusted by its set-screw to the desired position on the rod 24, beneath the table, according to the length of the snap to be twisted, and the end of the belt-shifting lever 28 is moved back, so as to engage against the end 100 of the lever 36, and the power can then be applied to the driving-pulley 57 to actuate the machine.

I connect the plates 4 and 5 firmly one to the other by bolts or rivets, as before mentioned, 10, with a short piece of tube placed between said plates and around each bolt or rivet. By this construction said plates are rigidly connected, but a sufficient distance apart to permit the toothed wheels 17 and 18 to be secured and revolve between them.

In the above-described mechanism the spring 12, the post 10, with its projections 11, and the wire 9 are combined with the teeth on the upper end of the spool, to form an automatic tension; and the combination of this tension mechanism with the spool holders or spindles 7 and all the mechanism located above and connected with each toothed wheel 17, and which is rotated by and with each said toothed wheel, I 115 denote the "racer," and designate it by the reference-numeral 6, marked at or near the disk which supports most of the said mechanism.

It will be seen from the above description 125 that in the operation of twisting snaps by my invention I am enabled to produce a varied combination of movements of the racers and plates, by which the quality of the twisted material may be correspondingly varied. For example, if the plates 4 and 5 are held stationary by the friction-roll while the racers are re-

volving on their own axes, the strands may be twisted to any desired degree of hardness, and if the pressure of the friction-roll upon the plate 5 is removed the plates will immediately

5 revolve around the axis of the tube, and the racers will remain stationary as to any rotary movement on their own axes, this change of movement operating to twist the twisted strands together, above the head 15, to any 10 desired degree of hardness.

In the operation of twisting the separate threads or strands, as they become shorter they draw upward upon the springs 12 and lift the wires 9 out of the ratchet-teeth on the upper 15 ends of the spools, and the latter are allowed to revolve and permit the thread to be unwound therefrom until, the tension upon the springs being relieved thereby, the wires again drop into engagement with the teeth on the

20 spools and hold them stationary to keep the threads taut while being twisted. After each strand between its spool and the head has been sufficiently twisted the pressure of the friction-roll 14 upon the plate 5 is released or

25 partially released, as desired, allowing the plate 5, which had before remained stationary, to revolve and twist together the strands above the head, and their pressure upon the head during this operation forces the rod 3 downward, and,

30 by the band or chain attached to the projection at its lower end, raises the weight 30, which in its upward movement strikes the dog 25 and moves the rod 24 upward, tripping the lever 36, and releases the belt-shifter, and stops 35 the machine automatically. The twisted snap being then completed, two knots may be tied a little distance apart, between which to sever the snaps from each other. The lever 28 is engaged with the trip-lever 36, and the power

40 being then again applied the process is repeated. The weight on the cord a little more than balances the rod 3; but as the snap is twisted the force or pressure of the strands upon the head of the rod 3 forces said rod

45 gradually downward. When one snap has been finished the operator seizes the twisted snap above the head and pulls it upward, unwinding the threads from the spools of the racers about the length of another snap. The rod is 50 elevated by the action of the weight when the pressure of the threads or strands on the head is removed.

In this last operation of twisting the separate threads together the rotary movement of the plates tends to untwist the single threads which had been twisted; but by forcing the friction-roll 14 down upon the plate 5 with just the degree of pressure to slightly check the plates in their rotary movement the racers will

be caused to rotate slowly on their axes, just 60 enough to maintain the original twist of each separate thread while they are being twisted together.

By the use of the friction-roll 14, as used in connection with the plates or some similar suitable retarding brake or check applied to the plates, I am enabled to revolve the latter either faster or slower, with a correspondingly diminished or increased rotation of the racers, and thereby accommodate the action of the 70 machine to the different kinds of material being operated upon, and I am enabled to do this by merely applying the brake or friction-roll to the plates or releasing it therefrom while the machine is in motion, and am not 75 obliged to stop the machine at all in making any change of relative movement between the plates and racers.

As the purpose of the plates 4 and 5 is jointly 80 to support and carry the racers, and both are firmly connected together, they may very properly be treated as one, and be termed the "carrier."

Having thus described my invention, what I claim as new is—

1. The combination of a vertical tube, 2, provided with a toothed wheel, a vertically-movable rod, 3, extending through said tube, a balance-weight connected with the lower end of said rod, a thread-supporting head fitted to 90 revolve upon the upper end of said rod, a carrier loosely fitted to revolve upon said tube, a series of revolving racers, each containing a spool, a tension device having a toothed wheel secured thereto, and a friction-roll to impinge 95 upon said carrier to control its rotary movement and that of the racers, substantially as described.

2. The combination of a vertical tube, 2, provided with a toothed wheel, a vertically-movable rod, 3, extending through said tube, a balance-weight, 30, connected with the lower end of said rod, a thread-supporting head fitted to revolve upon the upper end of said rod, a carrier loosely fitted to revolve upon said tube, a 100 series of racers each containing a spool, a tension device having a toothed wheel secured thereto, a friction-roll to impinge upon and control the rotary movement of said carrier and racers, a longitudinally-sliding rod, 24, provided with an adjustable dog, 25, adapted to be operated by the weight 30, and belt-shifting devices operated by said bar 24, substantially as described.

CHARLES E. WILLIAMS.
